UNITED STATES PATENT OFFICE.

JOHN E. SNYDER, OF SWISSVALE, PENNSYLVANIA, ASSIGNOR TO THE WESTINGHOUSE MACHINE COMPANY, A CORPORATION OF PENNSYLVANIA.

TURBINE-BLADING.

941,389.

Specification of Letters Patent. Patented Nov. 30, 1909.

Application filed May 16, 1908. Serial No. 433,249.

To all whom it may concern:

Be it known that I, JOHN E. SNYDER, a citizen of the United States, and a resident of Swissvale, in the county of Allegheny and State of Pennsylvania, have made a new and useful Invention in Turbine-Blading, of which the following is a specification.

This invention relates to elastic fluid turbines and more particularly to blading for turbines.

An object of this invention is the production of a simple, effective and relatively cheap means for blading turbines.

Two methods of blading turbines are now quite generally employed. Each method employs blade-carrying elements provided with blade-mounting slots in which the blades are secured. Each slot is adapted to receive but one row of blades.

The method most generally utilized employs separate calking or spacing pieces which are located in the blade-mounting slot between adjacent blades of a row and which are transversely expanded by a calking pressure and caused to grip the exposed faces of the blades and the walls of the slot and to thereby secure the blades to the blade-carrying element.

In the other method the blades are assembled in segmental strips and the strips are then secured into the blade-mounting slots. Various means are employed for assembling the blades in segmental strips and various means have been employed for securing the segmental rings to the blade-carrying elements. The most commonly employed is a segmental base strip which is provided with slots in which the faces of the blades are secured and which, after the blades are in place, is mounted, by means of a calking strip, into the blade-mounting slot.

My invention is entirely different from either of these methods of mounting blades but, while it is unlike both of them, it is in some respects similar to each of them. I contemplate providing blade-mounting slots in the blade-carrying elements, each of which are adapted to receive more than one row of blades. The blades of each row are spaced by means of spacing pieces which are located within the slots and between adjacent blades and which, with the blades, are secured in place by means of segmental base rings.

In the drawings accompanying this appli-

cation and forming a part thereof: Figure 1 is a fragmental section (taken longitudinally of a turbine) of the blade-carrying element of a turbine and discloses blades secured to the blade-carrying element in accordance with my invention; Fig. 2 is a similar section of a blade-carrying element with the blades removed and discloses the shape of the blade-mounting slot; Fig. 3 is a perspective view of one of the separate spacing pieces utilized in carrying out my invention; Fig. 4 is a perspective view of a segment of one of the segmental blade-mounting rings; Fig. 5 is a fragmental view of a blade embodying my invention; Fig. 6 is a perspective view of a locking strip which forms a detail of my invention; Fig. 7 is a perspective view of a modified form of locking strip; Fig. 8 is a fragmental section of a blade-carrying element along the line A—A of Fig. 9 and discloses a modified form of the blade-mounting slot; Fig. 9 is a section along the line B—B of Fig. 8; and, Fig. 10 is a perspective view of a detail of my invention.

Throughout the specification and in the claims, I will utilize the word "blade" in its broadest sense, that is, to mean either the rotating or the stationary blades and I wish it to be understood that I do not desire to limit my invention to either the stationary or the rotating blades and it will be obvious to those skilled in the art that my invention may be employed in mounting the blades of rotary compressors, exhausters and like machines as well as in mounting turbine blades.

Referring to the drawings and more particularly to Figs. 1 and 2: the blade-carrying element 11 is provided with a blade-mounting slot 12 which is formed in the peripheral face of the blade-carrying element and which is adapted to receive three rows of blades 13. Intermediate spacing pieces 14 are located within the slot and between adjacent blades of each row, and these spacing pieces, with the blades, are secured in place by means of segmental blade-holding rings 19 which are located within the slot and which are in turn secured to the blade-carrying element by means of segmental locking strips 15, which are located within the blade-mounting slots and are secured to the blade-carrying element by means of screws 16.

A notch 17 is cut in each edge of each

blade 13 and is located near one end of the blade. The spacing pieces 14 are so constructed that their top and bottom faces are parallel to each other and plain. The lateral faces are also parallel to each other and extend at right angles to the top and bottom faces. One end face, while it is perpendicular to the top and bottom faces, is concave and conforms in contour to the contour of the convex faces of the blade. The other end face is perpendicular to the top and bottom faces and is convex, conforming in contour to the concave face of the blades.

Each lateral face of the spacing pieces is provided with a longitudinally-extending slot 18 which is adapted to register with the notches 17 of adjacent blades when the pieces and the blades are located in place within the blade-mounting slot 12. A longitudinally-extending groove 20 is provided in one of the side walls of the slot 12 and is located near the top of the slot. This groove 20 is adapted to coöperate with the notches 17 and slots 18, formed respectively on one side of the blades and spacing pieces assembled in one row, in securing in place a longitudinally-extending wire 22, which, when the blades are assembled in the blade-mounting slot, acts as a key to secure them to the blade-carrying element.

One or more ridges 23 are provided in the bottom of the slot 12 and extend longitudinally of the slots. These ridges are provided with tapped holes 24 and are employed in securing the locking strips 15 to the blade-carrying elements. The locking strips are wider than their mounting ridges and when secured in place overhang the ridges on each side and form longitudinally-extending recesses. Each blade-holding ring 19 is provided with a longitudinally-extending flange 27 which is formed near the bottom of the ring and which is adapted to project into the recess formed by the overhanging portion of the locking strip and thereby hold the ring in place.

Each ring is also provided with a longitudinally-extending bead 26 which is located on the same side of the ring as the flange 27 and is adapted to coöperate with the notches and slots provided respectively in the blades and spacing pieces in securing the blades and pieces in the blade-carrying elements. The blade-holding rings and the blade-mounting strips are preferably cut into short segments for convenience in mounting the blades.

In assembling the blades and spacing pieces and securing them to the blade-carrying elements the following method is preferably employed. The wire 22, which, if desirable, may be cut in short sections, is located in the notch 20 and a few of the blades 13 and intermediate spacing pieces 14 of the first row of blades are located in place

so as to secure the wire 22 within the recess formed by the slot 20 and the notches and slots 14 and 15. Segments of two blade-holding rings 19 are then introduced into the slot and are located back to back. The bead 26, formed on the segment of the ring adjacent to the blades located within the slot, coöperates with the notches of the blades and the slots of the spacing pieces to lock them in place, and the flange 27, formed on that segment, coöperates with an overhanging shoulder 28, formed on the wall of the slot 12, to hold the segment in place. The segments of each ring are then locked in place by securing a segment of locking strip 15 to the ridge 23 by means of the screws 16. This method is pursued until all of the blades of the first row and the blade-mounting rings employed to secure them in place are secured to the blade-carrying ele- 85

After all of the blades 13 and spacing pieces 14 of the first row of blades are in place and the segmental rings 14 securely locked to the blade-carrying element, the second row of blades is secured in place in much the same manner. The blades and intermediate spacing pieces of the second row of blades are, however, located on the locking strip 15 of the first row of blades 95 and are secured in place between blade-mounting rings 19. The notches and slots formed respectively on both sides of the blades and spacing pieces coöperate with the beads 26 formed on the adjacent blade-mounting rings to lock the blades in place. The blades of each successive row are secured in place by blade-mounting rings 19 and the rings, as described, are secured in the locking strip 15. 105

The blade-mounting rings of the last row of blades, secured in a slot 12, are secured in place by a modified form of locking strip. This modified form of strip is of greater width than the strip shown in Fig. 6 and its peripheral face is flush with the peripheral face of the blade-carrying element. 110

In Fig. 8 a modification of my invention is illustrated. The blade-mounting slot 12 in this modification is provided with the ridges 23, shown in Fig. 2, but the construction differs from Fig. 2 in that the locking strips 15 are integrally formed with the ridges. Each wall of the slot is provided with an overhanging shoulder 28, the modified form of locking strip 15 as illustrated in Fig. 6 having been done away with. 115

In order that the blade-mounting rings 19 may be mounted in the separate slots into which each slot 12 is divided by the ridges 23, the blade-mounting strip or flange 15 of each ridge is cut away as shown in Fig. 9 to form an undercut slot 30. The width of each slot is sufficient to admit the segments of the blade-holding rings 19 into the slots. 125 130

A wedge-shaped or dovetailed key 31 is adapted to lock the blade-mounting rings in place by being inserted into the undercut slot 30 and is itself held rigidly in place 5 between adjacent blade-mounting rings by the undercut walls of the slot. The last blade-mounting rings mounted in a slot 12 are introduced into the slot through a slot 32 formed in the overhanging shoulder 28. 10 This slot obviously can not be undercut and the retaining key 33 for the blade-mounting rings is rectangular and is secured in place by means of screws.

In accordance with the provisions of the 15 patent statutes, I have described the principle of operation of my invention, together with the apparatus which I now consider to represent the best embodiment thereof, but I desire to have it understood that the apparatus shown is only illustrative and that the 20 invention can be carried out by other means.

What I claim is:

1. In combination with a blade-carrying element provided with a slot, a plurality of 25 rows of blades mounted in said slot, blade-mounting rings for securing said blades in place and locking strips secured to said blade-carrying element for locking said blade-mounting strips in place.

30 2. In combination with a blade-carrying element provided with a slot, a plurality of

rows of blades mounted in said slot, intermediate spacing pieces located between adjacent blades of each row, blade-mounting rings located between adjacent rows of blades for securing said blades in place and locking strips secured to said blade carrying element for locking said blade-mounting rings in place. 35

3. In combination with a blade-carrying 40 element provided with a slot, a plurality of rows of blades mounted within said slot, segmental blade-mounting rings located between adjacent rows of blades for securing said blades in place and a locking strip supporting a row of blades and adapted to 45 be said blade-mounting rings in place.

4. In combination with a blade-carrying element provided with a slot, a plurality of rows of blades in said slot and having 50 notched edges, blade-mounting rings having ribs to engage the notches for positively securing said blades in said slots and locking strips for positively securing said rings to said blade-carrying element. 55

In testimony whereof, I have hereunto subscribed my name this 12th day of May, 1908.

JOHN E. SNYDER.
